UNITED STATES PATENT OFFICE.

FRANK W. STECHAN, OF OAKLAND, CALIFORNIA.

ADJUSTABLE AND REVERSIBLE BOOK-MARK.

1,232,116.

Specification of Letters Patent.

Patented July 3, 1917.

Application filed November 29, 1916. Serial No. 134,026.

To all whom it may concern:

Be it known that I, FRANK W. STECHAN, a citizen of the United States, and a resident of Oakland, in the county of Alameda and State of California, have invented a new and Improved Adjustable and Reversible Book-Mark, of which the following is a full, clear, and exact description.

My invention relates to a book mark of the type having a movable pointer, and more particularly the invention relates to a book mark of the indicated type in which a slotted flat strip is provided with a pointer or pointers adjustable longitudinally of the strip to be positioned at any point along the same, the pointer being disposed either to the right or to the left, or two pointers may be employed disposed in the same direction or in opposite directions. Each pointer comprises plates at opposite sides of the strip and an intermediate block snugly fitting the slot of the strip, the plate on each side comprising a pointer head and a guiding base, the said pointer heads and guiding bases being within the side edges of the strip whereby they are protected by the strip so that the pointer will not penetrate the leaves and will not itself be damaged by catching on any other object.

Reference is to be had to the accompanying drawings forming a part of this specification in which similar reference characters indicate corresponding parts in all the views.

Figure 1 is a perspective view of a book mark embodying my invention, showing the same in use in a book, the mark being equipped with a single pointer;

Fig. 2 is a face view of the mark equipped with two pointers disposed in the same direction;

Fig. 3 is a view of the book mark shown in Fig. 2 but bodily reversed to dispose the pointers in the opposite direction from the positions in Fig. 2;

Fig. 4 is a view similar to Figs. 2 and 3 but showing the two pointers disposed in opposite directions;

Fig. 5 is a cross section on the line 5—5, Fig. 2.

In forming a marker in accordance with my invention, an oblong flat strip 10 is produced of paper, metal, celluloid, or other suitable material. The said strip is formed

with a longitudinal slot 11, thereby producing flat side bars 12 and end bars 13.

The strip in the form shown in Fig. 1 is equipped with a single pointer. In Figs. 2 to 4, the strip is provided with two of said pointers.

Each pointer, as best seen in Fig. 5, comprises two face plates 14 on the opposite sides of the strip 10 and an intermediate block 15 which is oblong has a snug fit in the slot 11, so that the pointer may be moved longitudinally of the strip and have sufficient frictional engagement therewith to retain the pointer in adjusted position.

Each face plate 14 is formed at one side into a pointer head 16, and at the opposite sides of the slot, the plate is formed with a guiding base 17. It is to be observed that the pointers terminate at or within the side edges of the strip 10 to be thereby protected at all times by the strip and be prevented from catching on the book leaves or other objects.

In Fig. 2 both pointers are disposed in the same direction and the book mark may be bodily reversed to dispose the two pointers in the opposite direction as in Fig. 3. In Fig. 4 one pointer has its pointer head disposed toward the left and the other disposed toward the right. By bodily reversing the book mark a line on either page of a book A may be indicated by reversing the mark from the position shown in full lines Fig. 1 to that shown in dotted lines. With the two pointers disposed in reverse directions Fig. 4, lines on 2 pages may be indicated, or with the marker shown in Figs. 2 and 3, a particular paragraph or section of the page can be indicated between the pointers.

It will be clear by having the pointer formed with side plates having pointer elements at opposite sides, the book mark may be reversed endwise, that is to say, either end may be disposed at the top of a book, to reverse the direction of the pointer or turned over to present one face or the other uppermost, thereby optionally disposing the pointer to the right or to the left.

Having thus described my invention, I claim as new, and desire to secure by Letters Patent:

A book mark including an elongated flat

strip having a longitudinal slot thereby forming parallel side bars, and end bars connecting the side bars, and an indicating device comprising an oblong block fitting in said slot and slidable therein for movement along the strip, and flat face plates carried by the block at opposite faces thereof, said

plates each extending transversely of the strip and overlying the strip at both sides of the block, one end of each face plate being in the form of a pointer and said plates terminating at both ends within the side edges of the strip. 13

FRANK W. STECHAN.
